UNITED STATES PATENT OFFICE

2,045,170

AGITATING MIXER

Frank Whipperman, Omaha, Nebr.

Original application August 23, 1934, Serial No. 741,073. Divided and this application March 23, 1935, Serial No. 12,710

1 Claim. (Cl. 34—7)

This invention has to do with the art of mixing machines in general and particularly with agitating mixers for drying, heating and mixing granular fuel material and the like in the method of 5 making fuel-blocks described in my application for patent of August 23, 1934, Serial Number 741,073, of which this application is a division.

Briefly the above mentioned method of making fuel-blocks consists in the drying and heating of 10 granular fuel material such as coal and coke screenings and fines and the like by pocketing therein hot combustion products from a suitable source of supply, mixing with the heated and dried fuel material molten asphaltic binder and 15 then blocking the hot mixed material.

To satisfactorily prepare the granular fuel material for blocking substantially all of the moisture contained therein must be driven therefrom and the material heated to a suitable temperature 20 for mixing with the molten binder.

In preparing granular fuel material for blocking in the making of fuel-blocks great difficulty has been experienced in drying and heating said material particularly when the moisture content 25 thereof is high as in certain lignites wherein often as much as forty or fifty percent of moisture may be present. Economical and efficient carrying out of any method of making fuel-blocks requires the rapid treatment of the granular fuel material 30 to quickly dry and heat same to reduce to a minimum the consumption of fuel required for said drying and heating of said material.

It is therefore an object of my invention to provide an agitating mixer for thoroughly drying 35 the fuel particles, heating the same sufficiently to insure the uniform coating of the particles with melted binder, and eliminating from the product water and certain volatiles and deleterious ingredients such as sulphur, while utilizing heating 40 values of such eliminated constituents to furnish a portion of the heat required for the preparing operation, and thereby effecting the drying and heating of the material with a minimum expenditure of fuel.

Another object of my invention is to provide an 45 agitating mixer wherein fuel material that has been thus dried and heated may also be mixed with liquid binder.

A further object is to provide a mixer of the type 50 described that is relatively inexpensive to manufacture, and that is simple in construction and operation.

Other objects of my invention will appear in 55 the following detailed description taken in connection with the accompanying drawing wherein:

Figure 1 is a plan view of my invention with the cover removed to show the interior of the machine.

Figure 2 is a section through the mixer and operatively associated furnace.

Figure 3 is a cross-section of the mixer blade. 5
The drying, heating, expulsion of volatile and 10 vaporous matter from the granular fuel material and the mixing of the binder with said fuel material may be all effected in my agitating mixer, the preferred embodiment of which is represented in the drawing which is now more particularly referred to. Reference numeral 16 indicates a cylindrical body closed at the ends by end members 17 which extend downwardly and are secured to longitudinal base-members 18 15 adapted to be bolted or otherwise secured to a floor or base. The body 16 is provided with a central opening 19 in the top thereof through which granular fuel material to be treated and prepared for blocking is admitted from a supply 20 hopper 20. Doors 21 are provided at the lower end of the hopper 20 and said doors may be opened to permit fuel material to pass from the hopper into the cylindrical body. The doors 21 are normally closed to retain the next batch of 25 fuel material in said hopper until the previous batch has been treated in the agitating mixer and discharged therefrom and the mixer is ready to receive the succeeding batch of material. An outlet 22 is provided in the lower body wall 30 through which treated fuel material is discharged into a receiving hopper 29 of a blocking machine, not shown, upon the opening of a door 24 which normally closes said outlet 22.

Agitation of materials in the cylindrical body is 35 effected by a plurality of part-helical blades 25 mounted on supporting arms 26 secured to a square shaft 27 rotatably mounted centrally of the cylindrical body and having the ends thereof mounted in heat-resisting bearings 28 spaced 40 outwardly of the end members 17 to position said bearings away from the heat within the body. The blades 25 extend inwardly from their respective ends substantially two-thirds the length of the cylindrical body thus their respective spheres 45 of agitation within the body overlap causing the fuel material therein to be worked toward the longitudinal center of the cylindrical body with a rotating, oscillating movement thereby more thoroughly agitating the fuel material. Each 50 blade is provided with a flange 29 extending outwardly and slightly downwardly from the lower edge thereof, said blade and flange forming an obtuse angle in cross-section as shown in Figure 3. It should be noted that the flanges extend 55

outwardly of the blades in the direction of rotation of said blades.

In operation the blades enter material in the body at an angle and plow through it much as 5 would the mold-board of a plow. The material is scooped up by the blades and a substantial portion thereof retained on the flanges until the 10 respective portions of the flanges pass the upper vertical center of the cylindrical body where the downward inclination thereof causes said retained material to drop therefrom as the blades 15 rotate thus forming a wall or barrier of the falling material, said material, as it is dropped, being interposed between opening 32a, the inlet for hot combustion products, and outlet 36.

Heat for drying and heating the batch of material in the mixer is supplied from a furnace 30 preferably positioned beneath the mixer though it may be placed at the rear thereof or 20 in any other suitable position. In the preferred embodiment the agitating mixer is mounted on the furnace as shown in Figure 2. The mixer body is provided with the inlet 32a adapted to receive hot combustion products downwardly into 25 said body from a flue 31 from said furnace, said flue having an outlet 32 of reduced dimensions in register with said inlet 32a. The flue has a fire-brick arch 33 at the top thereof that directs the 30 heat, gases and flames downwardly into the mixer and is also provided with a wall 34, transversely pointed at the top, said pointed top extending into the archway of the flue. The upper point of the wall 34 is higher than the lower edge 35 of the arch of the flue thereby forming a baffle to prevent the heat, gases and flames from 35 the furnace from normally passing directly across the top portion of the mixer and out the outlet 36 therein. The bottom or ash-pit doors of the furnace, not shown, are normally kept 40 closed. A blower 37 delivers air into the ash-pit 38 through an opening 39 in the furnace wall, whereby forced draft may be applied to the furnace, and the volume of air passing through said furnace effectively regulated.

45 Coal screenings and fines are conveyed to and deposited into the hopper 20 by any suitable means such as an elevator conveyor. Said screenings and fines vary in size from fine dust to about $\frac{3}{4}$ inch pieces such as would pass 50 through the mesh of a screen and certain definite amounts thereof are batched by weight or otherwise and allowed to pass from the hopper 20 into the mixer by regulation of the doors 21.

55 The material is then thoroughly agitated, rolled and tumbled in the mixer and dropped from the flanges 29 of the blades 25. The heat and gases from the furnace are somewhat compressed as they pass through the reduced outlet 32 of the flue and as they leave the flue they expand in the mixer. Said heat and gases are directed downwardly by the arch of the flue directly into the agitated mass of fuel material in the lower portion of the mixer and the material 60 dropped from the blades 25 cover and pocket said heat and gases. The blades then agitate the heat and gases and fuel material and thoroughly mix same together.

65 In this manner the material is dried and the wet gases and vapor from the material escape 70 from the mass of material and pass out the outlet 36. The blades are diametrically opposed to each other in the mixer. While the upper blade is pocketing heat and gases and passing the inlet 75 32a, the opposite blade is approaching said inlet.

During a brief interval after one blade has passed the inlet 32a and the opposite blade has not yet reached the outlet no barrier is presented to the heat and other combustion-products entering the inlet and they will pass from the inlet, into the 5 mixer, and leave through the outlet 36 without being mixed with the material in the machine. A draft is thereby created which clears the upper part of the mixer of all moist vapors and gases. The rising blade then passes the outlet 36 and 10 drops material from the flange, stopping the direct passage of heat and gas from the inlet across the upper portion of the body and out through outlet 36. Due to the blades not extending 15 the entire length of the body of the machine there is a slight draft around the inner ends of the blades at all times to aid in the expulsion from the machine of moist vapors and gases driven from the material being treated.

It is found in practice that by supplying sufficient heat to the mixer by the burning of outside coal or other fuel to evaporate the moisture in the granular fuel material in the machine and raising the temperature thereof by pocketing said outside heat in the material being treated, self or 25 internal heating of the fuel in the machine is brought about by the combustion of volatiles and dust of said material, and this self or internal heating of the fuel is then carried on automatically until the proper temperature for mixing of the 30 material with the binder is reached. This burning of volatiles and dust within the machine effects a marked reduction in the total amount of fuel required to assure the drying and heating of 35 the granular fuel material to the desired temperature because of the direct application to and generation of heat within the material itself. Also by the described mode of operation, discharge of unburned volatiles and dust into the air is avoided, and there is no liability or danger of explosions 40 by accidental ignition of dust, or unburned volatiles, expelled from the granular fuel material by the heating thereof to the temperatures desirable 45 for mixing with binder material and for the blocking operation. Ignition and burning of the material itself is prevented by the constant tumbling and agitation thereof by the blades and the drying and heating is so controlled that the temperature of the material being treated may be raised in the mixer to any desired point at which 50 said material is best suited for mixture with the binder and for blocking.

After the material is thoroughly dried and heated liquid asphaltic binder of suitable character and amount is admitted, by suitably controlled 55 means, to the mixer and the heated and dried fuel material and liquid binder are worked, agitated and mixed until all the solid particles are effectively coated with a thin film of the binder, and the mixed material is then discharged from the 60 machine into the receiving hopper 23 of a blocking machine.

It is to be understood that the heating of the mass of granular material and binder continues while the mixing thereof is effected to prevent 65 cooling thereof, during the mixing operation, to a temperature below which satisfactory blocking could be effected.

70 My agitating mixer is relatively simple and inexpensive to manufacture, and the cost of treating and mixing granular fuel material with a suitable binder with my mixer, proportional to the output thereof, is very low, so that said treatment may be effected economically, while increasing the value of the coal or coke screenings and fines to 75

equivalence with that of the respective unbroken fuel.

It is, of course, to be understood that the invention may be constructed in other manners and the parts associated in other relations, and, therefore, I do not desire to be limited in any manner except as set forth in the claim hereunto appended.

Having thus described my invention, what I claim and desire to secure by Letters Patent is:

An agitating mixer for treating granular fuel material such as coal and coke screenings and fines and the like in the production of fuel-blocks, comprising a horizontal, substantially cylindrical body having an inlet for hot combustion products adjacent the top of the body and on one side of the vertical center thereof adapted to admit hot

combustion products downwardly into said body, and an outlet for vapors and gases adjacent the top of the body and on the opposite side of the vertical center from the inlet, and a plurality of blades extending longitudinally of the body and 5 rotatably therein, each of said blades having a flange thereon, said blades being adapted, upon rotation thereof, to carry granular fuel material to the upper portion of the body and then drop said material toward the inlet and downwardly 10 to the lower portion of the body, to pocket hot combustion products, admitted through the inlet, in the granular fuel material, said dropped material extending transversely of the current of hot combustion products admitted through said inlet. 15

FRANK WHIPPERMAN.
